JEWELRY

Ralph C. Bangs, Providence, R. I., assignor to
 Cohn & Rosenberger Inc., New York, N. Y., a
 corporation of New York

Application February 25, 1938, Serial No. 192,459

1 Claim. (Cl. 40—142)

My invention relates to a new and improved article of jewelry.

One of the objects of the invention is to provide an improved brooch or pin although the invention is not restricted to any particular use.

Another object of the invention is to provide a frame of simple construction, and to provide letters, initials or characters which can be simply and conveniently connected to said frame or be detached from said frame.

Another object of the invention is to provide a device which can be made at low cost and which will be of simple and durable construction.

Another object of the invention is to provide a frame in the form of one or more pairs of bars, said bars being made of resilient metal or other resilient material, said bars defining slots into which rigid lugs or heads of the characters can be inserted and held frictionally.

Other objects of my invention will be set forth in the following description and drawing which illustrates a preferred embodiment thereof, it being understood that the above statement of the objects of my invention is intended generally to explain the same without limiting it in any manner.

Fig. 1 is a front elevation of the improved device.

Fig. 2 is a rear elevation of said device.

Fig. 3 is a sectional view on the line 3—3 of Fig. 2.

Fig. 4 is an enlarged partial view of the frame member and of certain other parts of the device.

Fig. 5 is a sectional view on the line 5—5 of Fig. 4.

The device comprises a frame member 18 which is provided with one or more longitudinal slots 19. The frame 18 is made of suitable resilient metal or other resilient material so as to provide resilient bars whose edges define the slot or slots 19. Said resilient bars are separated from each other by the cross-portions of the frame 18 which are located between the slots 19.

The drawing also shows characters L', L² and L³, which are initials in the specific embodiment which is illustrated herein, as said embodiment illustrates an initial pin or initial brooch.

Fig. 1 and Fig. 2 show the characters partially overlapping each other and this is an important ornamental feature of the device, whereby a very attractive effect is secured.

The respective characters are provided with means which are identical in construction for connecting said characters releasably to the frame 18, although said connecting means may

differ in dimensions in order to secure the aforesaid partial overlapping effect.

As shown in Fig. 5, the rear face of each of the characters, such as the character L², has a bracket 10 connected thereto by means of soldering or the like. The bracket 10 has an arm 11 which is soldered or otherwise connected directly to the character L². Said character L² and the other parts described herein are made of any suitable metal or other material.

It would not be departing from the invention if the bracket 10 were integral with or connected in any suitable manner to the respective character.

Each bracket 10 is provided with a laterally extending arm 12. Each arm 12 is provided with an enlarged head which includes spaced head-portions 13 and 14, and an intermediate portion 15. Each arm 12 is therefore provided with a groove intermediate the adjacent walls of the head-portions 13 and 14.

In order to connect each character to the frame 18, the head-portion 14 is pushed through the slot 19. The resilient bars of the frame 18 can spring apart or be sprung apart by a tool. Said bars then spring into the groove intermediate the members 13 and 14 so as to hold the inner end of the bar 12 frictionally and firmly in position. The bars 11 and 12 and the members 13 and 14 are preferably made of rigid and non-springy metal.

Fig. 5 shows the edge 16 of the member 13. If desired, the member 14 may be twisted relative to the longitudinal axis of the bar 12, so as to form edge-portions 17 which overlie the inner wall of the frame 18, when the character is held on the frame 18. This is shown in exaggerated form in Fig. 4.

The invention is not to be limited to said twisting of the member 14.

In Fig. 5, the adjacent inner edges of the bars of the frame 18 are shown as being slightly spaced from the adjacent walls of the member 15, for clearness of illustration.

If desired, the inner surfaces of the bars of the frame 18 may frictionally abut the corresponding surfaces of the member 15. The fit of the bars of the frame 18, between the members 13 and 14, is preferably a close fit.

If desired, the resilient frame 18 may be made sufficiently stiff so that it requires a tool in order to separate the bars thereof, so as to spring the member 14 through the slot 19, and into the position shown in Fig. 4 and in Fig. 5.

While the characters may be slid in their slots 19, by the use of sufficient force, the fric-

tional grip of the frame 18 upon the arms of the carriers is sufficient to hold said characters firmly in their adjusted position.

The frame 18 may be provided with any conventional means for holding it to a garment. For example, Fig. 3 shows the usual pin 21 which is turnably connected to a lug 20. Said lug 20 is suitably connected to one end of the inner wall of the frame 18. The other end of the inner wall of the frame 18 may be connected with the usual latch 22, for holding the pin 21 releasably in position. This detail is not illustrated as it is old and well known per se.

As shown in Fig. 3, the bars 12 of the brackets 15 of the respective characters may differ in length, in order to permit the partial overlapping of the characters.

When a brooch of this type is sold, the dealer selects the proper characters such as the initials 20 of the purchaser. The slots 19 can then be enlarged by spreading apart the bars thereof by means of a suitable tool. The members 14 are then sprung through the slots 19 so that the bracket arms 12 assume the positions illustrated 25 in Fig. 3. The characters are then held firmly and immovably in the frame 18, although said characters may be readily removed by the use of a suitable tool.

The member 14 is of tapered shape, both in 30 the horizontal plane and in the vertical plane as shown in Fig. 3 and in Fig. 5.

As shown in Fig. 3, the respective characters are preferably held in separate slots 19 of the frame 18 and these characters are preferably inclined to the frame 18. It is preferred that each 35 of the slots 19 be closed at each end thereof.

For convenience, the device will be described and claimed with reference to the vertical position of the characters which is illustrated in the drawing.

The height of the head which comprises the members 13, 14 and 15 is preferably less than the width thereof, as can be seen by a comparison between Fig. 3 and Fig. 5. As shown in Fig. 40

4, the slot 19 has a general rectangular shape so that it has two long sides, and two short sides. For convenience, the long dimension of the slot 5 may be designated as the width thereof, and the short dimension of the slot may be designated as the height thereof. The dimension of the member 15, in a direction parallel to the long sides of the slot 19, may be designated as the width of the member 15. As shown in Fig. 2, the height 10 of each slot is less than the width thereof, so that each slot has a longitudinal axis which is parallel to the long sides of the slot. The longitudinal axes of said slots are coincident. The portion 15 of each head may be designated as the reduced portion of said head. 15

I have shown a preferred embodiment of the invention, but numerous changes and omissions can be made without departing from its spirit.

I claim:

An ornamental device comprising a frame 20 made of resilient material and having a plurality of separate slots which are spaced from each other, the height of each slot being less than the width thereof so that each slot has a longitudinal axis which is parallel to the long sides 25 of said slot, the longitudinal axes of said slots being coincident, ornamental members, each said ornamental member having a head extending laterally and rearwardly therefrom, each said head comprising laterally spaced head portions 30 and an intermediate reduced portion, the resilient walls of said slots engaging said heads and said reduced portions and frictionally holding said ornamental members in partially overlapping relation, the width of each slot being greater 35 than the width of the respective reduced portion, each reduced portion being slidably in the respective slot in a direction parallel to the long sides of the respective slot, the inner surfaces of the walls of said slots substantially abutting the respective adjacent surfaces of the respective reduced portion. 40

RALPH C. BANGS.
